UNITED STATES PATENT OFFICE.

FRED W. WOLF, OF CHICAGO, ILLINOIS, ASSIGNEE, BY MESNE ASSIGNMENTS, TO ISKO,
INCORPORATED, OF DETROIT, MICHIGAN, A CORPORATION OF MICHIGAN.

HEAT-INSULATING MATERIAL.

1,198,984.

Specification of Letters Patent. Patented Sept. 19, 1916.

No Drawing.

Application filed September 11, 1914. Serial No. 861,195.

To all whom it may concern:

Be it known that I, FRED W. WOLF, a citizen of the United States, and a resident of Chicago, in the county of Cook and State 5 of Illinois, have invented certain new and useful Improvements in Heat-Insulating Material; and I do hereby declare that the following is a full, clear, and exact description thereof.

10 This invention relates to an article of manufacture comprising a heat insulating material and consists of the matters herein-after described and more particularly pointed out in the appended claims.

15 The new article of manufacture is primarily intended for use as a heat insulator in the construction of refrigerators, cooling boxes and the like, but it will be understood that it is not limited thereto.

20 In the preferred use of the material, it provides a filler or packing between the usual double walls of the refrigerator.

My improved article of manufacture consists preferably of fragments of cork of 25 various sizes, (that is to say, larger and smaller sizes) so that the fragments of cork may be made to substantially fill the space to be occupied by the material and of powdered or pulverized infusorial earth such as 30 kieselguhr. In preference I use about 85 to 90% by weight of cork to about 15 or 10% of kieselguhr. The two are mixed together dry, somewhat in the manner that concrete is mixed. As a result of the mixture, the 35 fragments of cork are coated or covered more or less with the finely divided flour of the kieselguhr and the spaces between the fragments of cork are filled and occupied by the flour-like, smaller particles of the 40 kieselguhr.

In the use of the material, as for example, when packing the space between the double walls of a refrigerator, the mixture is poured dry into the space. The refrigerator may 45 then be shaken or jarred to settle the mixture so that all of the available space will be occupied and all corners and interstices between the larger fragments of the material filled.

50 As is well known, cork in its natural, uncompressed state is not only a good heat insulator itself, but in addition contains a large number of non-communicating cells which are filled with air. If the fragments

of cork alone are used as a packing there 55 will be large inter-connecting air spaces throughout the conglomerate body composed of the fragments of cork and if in order to eliminate these spaces the cork is compressed so as to bring the fragments 60 closer together, the air contained in the cells of the cork is expelled by the pressure. The use of fragments of cork of various sizes minimizes and reduces the size of the air spaces between said fragments, while the use 65 of the powdered or flour-like kieselguhr, which also contains air cells, fills up, without pressure or tamping, the spaces between the fragments of cork. Thus a substantially solid packing entirely filled throughout with 70 innumerable non-communicating air cells is produced without expelling the air from the mixture. As a result the space to be occupied by the insulating material consists of a mixture of cork and earth filler which is per- 75 meated throughout with small bodies of the best known heat insulating substance, that is to say, air, and this air is so held in the packing that it is incapable of circulation and therefore of communicating the tem- 80 perature from one side of the filler to another. Thus in the mixture the air spaces between the fragments of earth and cork are not only finely divided and reduced in size, but are also sealed so that these spaces them- 85 selves become confined and cut off from communication, so that as a result, all of the air has its absolute heat insulating efficiency. The result is the production of a heat insulating material which has all the necessary 90 advantages combined with the highest efficiency and also a material which is comparatively cheap and easy to handle both before and in the process of packing it in the space that it is to be used. It is light, in fact, 95 much lighter than the nearest best insulator that could be obtained, namely, solid cork, which is almost prohibitive, not only in first cost, but also the cost and waste of handling when placing it in the refrigerator, 100 and adds greatly to the weight of the refrigerator.

Kieselguhr is preferred as the infusorial earth, to mix with the cork fragments, since when mixed with cork fragments as de- 105 scribed and substantially in the proportions mentioned, the kieselguhr particles will maintain their relative initial positions with

respect to the cork fragments and will not settle toward the bottom of the compartments containing the insulating mixture. Another advantage of this material, particularly when used for insulating purposes on a refrigerator is to be noted. In the case of refrigerators on which is placed a refrigerating apparatus including a motor or other device adapted to produce vibrations, 10 is that the material is a sound absorber and eliminates the noise generally occurring in connection with such refrigerating apparatus.

While I prefer the use of an infusorial 15 earth as the powdered or flour-like medium to fill the interstices between the fragments of cork, other powdered material which is a heat insulating medium in itself and which contains air cells, or when in bulk contains 20 air cells or is capable of inclosing air cells, may be used instead of the kieselguhr.

I claim as my invention:

1. A heat insulating material consisting of a dry mixture of fragments of cork and of powdered "kieselguhr," said insulating 25 material containing a greater percentage of cork fragments than "kieselguhr."

2. A heat insulating material consisting of a dry mixture of fragments of cork, of various sizes and of powdered "kieselguhr," 30 said insulating material containing a greater percentage of cork fragments than "kieselguhr."

In testimony, that I, claim the foregoing as my invention I affix my signature in the 35 presence of two witnesses, this 29th day of July A. D. 1914.

FRED W. WOLF.
